US0D1087201S

(12) **United States Design Patent** (10) Patent No.: **US D1,087,201 S**
(45) Date of Patent: ** Aug. 5, 2025

(54) **VIDEO SURVEILLANCE CAMERA**

(71) Applicant: **AJAX SYSTEMS CYPRUS HOLDINGS LTD**, Nicosia (CY)

(72) Inventor: **Iishat Garipov**, Haapsalu (EE)

(**) Term: **15 Years**

(21) Appl. No.: **35/520,940**

(22) Filed: **Apr. 19, 2024**

(80) **Hague Agreement Data**

Int. Filing Date: **Apr. 19, 2024**

Int. Reg. No.: **DM/237024**

Int. Reg. Date: **Apr. 19, 2024**

Int. Reg. Pub. Date: **May 24, 2024**

(51) **LOC (15) Cl. 16-01**

(52) **U.S. Cl.**

USPC **D16/203**
